UNITED STATES PATENT OFFICE

151,033

DESIGN FOR A POPCORN DISPENSING
MACHINE

Frank P. Emerson, Los Angeles, Calif.

Application April 19, 1946, Serial No. 128,780

Term of patent 14 years

(Cl. D52—3)

To all whom it may concern:

Be it known that I, Frank P. Emerson, a citizen of the United States and residing at Los Angeles, in the county of Los Angeles, State of California, have invented a new, original, and ornamental Design for Popcorn Dispensing Machine, of which the following is a specification, reference being had to the accompanying drawing, forming part thereof, in which:

Fig. 1 is a perspective view of a popcorn dispensing machine as seen from the front and one side thereof, showing my new design,

Fig. 2 is a perspective view of a popcorn dispensing machine as seen from the back and the other side thereof.

Fig. 3 is a plan view.

I claim:

The ornamental design for a popcorn dispensing machine, substantially as shown.

FRANK P. EMERSON.
